UNITED STATES PATENT OFFICE.

JOHN V. GODDARD, OF TRENTHAM, ENGLAND, ASSIGNOR TO HUGH C. EDMISTON, OF NEW YORK, N. Y.

DESIGN FOR A COVERED DISH.

Application filed November 11, 1924. Serial No. 11,344. Term of patent 3½ years.

To all whom it may concern:

Be it known that I, JOHN V. GODDARD, a subject of the King of Great Britain, residing at Trentham, county of Stafford, England, have invented a new, original, and ornamental Design for a Covered Dish, of which the following is a specification, reference being had to the accompanying drawing, forming part thereof.

I claim:

The ornamental design for a covered dish as shown.

JOHN V. GODDARD.
